DESIGN FOR A SCALE PANEL

John Watling, Chicago, Ill., assignor to Watling Scale Company, Chicago, Ill.

Application September 5, 1939, Serial No. 87,044

Term of patent 14 years

To all whom it may concern:

Be it known that I, John Watling, a citizen of the United States, residing at Chicago, in the county of Cook and State of Illinois, have invented a new, original, and ornamental Design for a Scale Panel, of which the following is a specification, reference being had to the accompanying drawing, forming part thereof.

Figure 1 is a front elevational view of a scale panel embodying my new design.

Figure 2 is a top plan view thereof.

I claim:

The ornamental design for a scale panel, substantially as shown.

JOHN WATLING.
